US0D1033989S

(12) **United States Design Patent** (10) **Patent No.:** **US D1,033,989 S**
(45) **Date of Patent:** **** Jul. 9, 2024**

(54) **PILLOW**

(71) Applicant: **QianQian Song**, Guangdong (CN)

(72) Inventor: **QianQian Song**, Guangdong (CN)

(**) Term: **15 Years**

(21) Appl. No.: **29/864,319**

(22) Filed: **May 20, 2022**

(51) LOC (14) Cl. **06-09**

(52) U.S. Cl.

USPC **D6/601**

(58) **Field of Classification Search**

(57) **CLAIM**

The ornamental design for a pillow, as shown and described.

DESCRIPTION

FIG. 1 is a top, front and right side perspective view of a pillow showing my new design;

FIG. 2 is a bottom, rear and left side perspective view thereof;

FIG. 3 is a front elevation view thereof;

FIG. 4 is a rear elevation view thereof;

FIG. 5 is an enlarged left side elevation view thereof;

FIG. 6 is an enlarged right side elevation view thereof;

FIG. 7 is a top plan view thereof; and,

FIG. 8 is a bottom plan view thereof.

1 Claim, 6 Drawing Sheets
